MACHINE FOR MAKING ROOFING AND THE LIKE

Alfred W. Kuettel, Duluth, Minn.

Application January 14, 1953, Serial No. 331,140

3 Claims. (Cl. 153—28)

This invention relates to a method and means for making standing seam metal roofing or the like.

As is well known, a good roof is a very vital part of any building. In order to obtain a good roof, one must use good materials and good workmanship, of course. The perfect roof would be of good material and have no seams or holes, however, it is not practical or possible to provide a perfect roof, especially for a large structure. In other words, the fewer the seams in the roof the better it is. Metal roofing comes closest to being the perfect roofing for fewer seams can be used with metal roofing.

One of the factors which has most control over the type of roof installed on a building, however, is its cost. Asphalt shingles have come to be generally accepted as the best buy for the initial investment for the average buyer because they are relatively cheap. The present metal roofing, though much more durable, especially if paint is applied thereto at regular intervals costs materially more than asphalt shingles to manufacture. Metal roofing must be made by hand tongs or brakes by highly skilled workmen who get high pay rates.

Another disadvantage of present metal roofing is that, because it is made with hand tongs or brakes, the seams are not straight and true and it is difficult to assemble and may leak at the seams slightly because of the irregularities in the seams.

Another disadvantage of present metal roofing is that it can only be made in relatively short lengths by braking devices and it is impractical to use hand tongs for manufacturing under present high labor rates, and, with hand tongs, one is quite limited in the shaping he can do.

Because of the limited lengths in which metal roofing now can be made, cross seams are required to seal the connection or joint between longitudinally connected units. These cross seams require extra forming labor, as well as extra installation labor for all cross seams must be locked and soldered.

Repeated expansion and contraction of the metal under changing weather conditions usually results in the breaking of the soldered seam and possible leaks at the cross seams. These cross seams are the most vulnerable part of present metal roofing.

In other words, metal roofing up until now, has not been priced where it could gain acceptance of the public, it has not had a neat enough appearance to be acceptable in any but rough construction where durability was the most important factor.

Asphalt shingle roofs will last from ten to fifteen years on the average, however, a metal roof will last indefinitely if painted at regular intervals. In spite of this comparative durability of metal over asphalt, metal has not come into general use for the reasons outlined above.

It is, therefore, one of my principal objects to provide a means for making metal roofing and the like of the standing seam type which will overcome the present disadvantages of such roofing and thereby bring this type of roofing and the like into more common use.

Another object is to provide a means for making standing seam roofing and the like in any length desired in a most simple, efficient and inexpensive manner whereby cross seams can be eliminated entirely thereby eliminating a great deal of installation labor and expense.

2

Another object is to provide a means for making material of this type wherein the manufacturing cost is reduced materially as well as is the cost of installation of the material.

5 Another object is to provide a means for making standing seam roofing and the like whereby the seams will be uniform and straight for easy installation and more secure and watertight connection.

10 Another object is to provide a means for making such material provided with a nailing strip along one edge whereby the installation of the material is simplified and extra attaching cleats or clips are not necessary.

15 Another object of my invention is to provide a means for making standing seam roofing and the like whereby the same can be made on a production basis and highly skilled, highly paid labor is not necessary for the making of the material thereby reducing the cost of manufacture materially.

20 Another object is to provide such material that can be applied with the good workmanship necessary for a good roof without highly skilled highly paid labor.

25 These and other objects and advantages of my invention will become more apparent as the description proceeds.

20 In the accompanying drawing forming a part of this invention:

Fig. 1 is a top plan view of a machine embodying my invention.

Fig. 2 is a sectional view on the line 2—2 Fig. 1.

30 Figs. 3, 4, 5 and 6 are elevational views of some of the successive roller dies used in forming my standing seam roofing and the like in their successive order.

35 Fig. 7 is an enlarged view of the final die used for one edge of the roofing showing the metal going through the die and the parts in exploded relation for clarity, it being deemed apparent that in actual practice the sheet metal would engage the die, and the ribs formed by the dies would be of less width and engage the width governing gauge which is located therein.

40 Fig. 8 is a view similar to Fig. 7 for the opposite edge of the roofing where no width gauge is used as the rib is very narrow.

45 Fig. 9 is an enlarged broken sectional view showing the die mounting that of the central roller.

Fig. 10 is an enlarged fragmental view partly in section showing the means for guiding one edge of the metal into the final die.

50 Fig. 11 is a view similar to Fig. 10 showing the opposite edge of the metal.

Fig. 12 is a fragmental perspective view showing how a roof is formed with metal made on my machine.

55 Fig. 13 is an enlarged fragmental sectional view on the line 13—13 Fig. 12 showing how the roofing is secured to the wood sheathing and how the standing seams are secured together by means of a pressed dimple, commonly referred to as button punching the metal together. The ribs are here shown in their true physical relationship when in use.

60 Fig. 14 is a broken fragmental perspective view showing the material shown in Fig. 10.

65 Fig. 15 is a view similar to Fig. 14, showing the material shown in Fig. 11.

In the drawings, the reference numeral 1 broadly indicates a base, which may be of any desired size, shape or dimension. A lower frame A, composed of a pair of elongated spaced parallel frame members 2—2, is rigidly carried on the base 1, each frame member having a suitable thickness and height to receive and carried a plurality of bearings 3, one of which is shown in Fig. 9. The bearings are mounted in opposite pairs, one of each pair being mounted in each of the opposed frame members 202 with their axes in alined relationship so as to rotatably re-

ceive one of the die carrying shafts 4. The pairs of bearings are spaced along the length of the frame so that a plurality of shafts 4 may be carried in spaced parallel relation to each other across the frame.

A central roller 5, of uniform cylindrical shape throughout its length, is mounted substantially centrally of the shafts 4 and is secured thereto to rotate therewith by a keyway, not shown or a set screw 6, forming a bed of aligned spaced rollers 5-5 which are securely mounted in their respective bearings. The rollers are so mounted that the highest point of their peripheries lie in the same plane.

The shafts 4 have one of their ends projecting beyond the frame to receive a drive gear 7, all drive gears being identical in size and number of teeth, of course. An intermediate gear 8 is provided between adjacent shafts 4 to drive one shaft from the other, and a central drive gear 9 is provided on one of the shafts 4 to receive power from any suitable motor, and thereby all rollers and shafts are driven simultaneously at the same speed and in the same direction.

Immediately above the frame members 2-2 are a pair of similar frame members 10-10 which are joined at their opposed ends to form a rigid rectangular upper frame B by a pair of spaced transverse members 11-11. The upper frame sits on top of the lower frame and is secured thereto by means of a plurality of spaced bolts 12-12 which extend freely through the frame members 10-10 and are threaded into tapped openings in the frame members 2-2, as indicated in dotted lines, Fig. 2.

An expansion spring 13-13 is provided on each of the assembly bolts 12 between the frame members 10 and the head of the bolt so that suitable tension may be applied to bias the frames A and B toward each other, yet permitting the raising and lowering of the frame B relative to the frame A when needed, as will become apparent.

The frame B is provided with a plurality of bearings such as the bearings 3, arranged in spaced opposed pairs immediately above the bearings of the frame A to receive a plurality of shafts 4' similar to the shafts 4 and directly above each of the shafts 4.

A cylindrical roller 5' similar to the rollers 5 is mounted on each of the shafts 4', and the rollers 5 and 5' are of such size and so arranged relative to each other and to the shafts 4 and 4' that they engage each other when the frames A and B are in engagement with each other, as shown in Fig. 2.

A gear 7' is mounted on an extending portion of each of the shafts 4', whereby each gear 7' engages the gear 7 immediately therebelow and is driven thereby so as to cause the rollers 5' and shaft 4' to rotate in the opposite direction to the rollers 5 and shafts 4.

It will be apparent from the above that an object which is placed between the rotating rollers 5 and 5' will be moved along in the direction towards which the adjacent surfaces of the rollers travel, and that as the object travels between the rollers 5 and 5', the bed of rolls carried by the frame B will be raised, against the tension of the upper rolls by the object passing between the rolls. Pressure will be applied to compress the object between the rolls.

It is to be noted that the central rolls 5 and 5' or the shafts 4 and 4' are spaced from the edges of the frame, and that a substantially cylindrical die roll 15 is carried on the shafts 4 and 4' adjacent each end of the rollers 5 and 5'. The dies in the upper frame being female dies, in the device here shown and the dies in the lower frame in general being male dies. The dies are so made and arranged as to make successive treatments to a sheet passed from the front C of the device to the rear D of the device.

There are four dies to each pair of shafts 4 and 4', as is apparent from the drawings. Each of the female dies has an annular groove, generally indicated by the numeral 16, therein, and the majority of their cooperative or male

dies have an annular rib 17 thereon each of which extends into its respective female die groove.

The dies have an inner end 18 and an outer end 19, and the grooves and ribs are so formed, and arranged on the shafts 4 and 4' that the inner edges of the grooves 16 and ribs 17 of the dies 15 on each end of the shafts 4 and 4' lie in a straight line in the direction of travel of an object through the machine, and these lines formed by the inner edges of the ribs and grooves form a part of spaced parallel lines.

The dies have grooves and ribs of progressively narrower width from the front C to the rear D of the machine, the narrowing of the ribs and grooves being from the outer ends toward the inner ends of the die rolls 15, that is the outer edges of the grooves and ribs of the dies do not lie in a parallel pair of lines.

Another characteristic of the die rolls 15 is that the diameter of the cylindrical inner ends of the dies 15 are the same as the diameter of the central rolls adjacent thereto so that a uniform gripping and driving effort is imparted to a sheet 20 being passed between the rolls throughout substantially its entire width. However the diameter of the cylindrical outer ends of the die rolls 15 is slightly less than the diameter of the inner end of the die roll.

This characteristic of the die rolls makes it possible for the outer edges of the metal sheet 20 to be drawn inwardly towards the center of the sheet so that the desired shaping of the metal can be obtained and still a central panel 21 is provided in the sheet having uniformly straight and parallel edges, the edges being bounded by ribs 22 and 23 upstanding from opposite edges of the sheet, as shown.

In the forming of standing seam roofing and the like a plurality of identical panels are formed, each having an upstanding rib along each longitudinal edge thereof, the rib 22 on one edge of the panels being wider than the rib 23 on the opposite edge of the panel whereby the panels may be placed in side by side relationship on the roof sheathing and the wider rib 22 will fit over the narrow seam 23 and the two ribs may be fastened together by means of a dimple impression 24 made simultaneously in the assembled ribs, see Figs. 12 and 13. This dimple impression assembly retains the panels in firmly assembled relationship and is referred to as "buttoning" in the trade.

In my device, I provide means for forming both of the ribs 22 and 23 as shown, for cooperative assembly, in a most convenient manner wherein the seams are straight and true and no difficulties are encountered in fitting the rib 22 over the rib 23 even when panels thirty feet and more in length are used.

In addition, I provide a nailing strip 25 on one margin of each panel, adjacent to and extending outwardly from the rib 23 to provide a means for securing the roofing securely to the sheathing by means of nails 26 or staples or the like not shown.

The final dies used in shaping the roofing material are the female die E and "male" die F used in forming the rib 22 and the female die G and "male" die H used in forming the rib 23. In addition a combination width guage and guide 27 is used in forming the rib 22. The guage member 27 comprises a strip of metal of the desired thickness to control the width of the opening in the rib 22, the strip being of suitable length to extend within the groove 16 in the die E and leave sufficient room on each side of the guage to receive the metal sheet 20 whereby the rib's size is controlled accurately throughout its length.

The guage 27 extends toward the forward end C of the device beyond the die E and between a pair of rollers 28-28, supported on a bracket 29 attached to the upper frame. The rollers are placed in side-by-side relationship just forwardly of the die E. The rollers 28-28 have their axles on which they rotate arranged in suitably spaced relationship whereby they provide room for the

guage to extend therebetween and also room for the metal. The rollers 28 are not driven but are rotated by their contact with the moving sheet 20 and serve to press the ribs 22 further toward their ultimate completed shape.

The guage 27 extends beyond the rollers 28—28 as well as beyond the die E and is supported by a bracket 30 attached to the upper frame. The foremost end of the strip or guage 27 is preferably rounded and bent or flared outwardly slightly as at 31 to pick up and guide the leading edge of each sheet as it approaches the rollers 28—28 and final die. It will be apparent that the outer edges of the sheet are being drawn inwardly as the sheet passes through the machine, and the guide 27 insures the sheets coming into proper register with the final dies, see Fig. 14.

The roller F is a plain roller, with no rib, the guide 27 takes the place of the rib.

On the opposite edge of the machine the final dies are G and H, and these latter dies are preceded by the roller 32 which engages the inner face of the rib 23, and the rigid guide 33 which engages the outer surface of the rib 23. Both the roller 32 and rigid guide 33 are carried on a bracket 34 secured to the upper frame.

The guide 33 has an arcuately shaped forward end which picks up and guides the rib 22 between itself and the roller 32 for further shaping towards its ultimate shape and serves as a guide to insure the rib 23 entering the groove 16 in the die G properly, see Fig. 15. In the final dies G and H, the rib 23 is made to be a very tight crease in the metal see Fig. 13.

As seen in Figs. 14 and 15, the ribs 22 and 23 are practically fully formed by the time they reach the final dies E—F, and G—H respectively and that these latter dies put the finishing touches on them to insure uniformity.

At the forward end of the machine I have placed a flat bed 35 on the lower frame and a flat guide 36 immediately above the bed 35 to insure the metal's entering the first dies in a flat condition, the bed and guide being relatively close to the first dies, as shown.

Fig. 12 shows a small segment of a roof with my material installed thereon to illustrate its use, and as is deemed apparent, any suitable length of material may be rolled in my device to suit the needs of the biggest roofs without the need for cross seams, which are costly to make and install and which are the most vulnerable part of any roof.

A roof of the material here made possible will last indefinitely with a minimum of service cost and labor, all that is required is a cost of paint at intervals depending on the climate and weather conditions.

It is to be noted that the cylindrical rollers 5 and 5' and the dies at each end thereof may be formed of one piece, that is, the cylinders can be elongated and the die grooves 16, and ribs, 17 could be formed therewith in a unitary part. However, I have preferred to make the dies separate members axially adjustably carried on the shafts 5 and 5', preferably by means of an elongated key 35 to provide positive driving for the die and a set screw 36 which secures the die in any desired adjusted relation between the adjacent frame and the cylinders 5 or 5'.

This arrangement permits the adjustment of the machine to the width of sheet to be rolled in a most efficient and convenient manner without necessitating the changing of shafting 4, rolls 5, or the like.

Having thus described my invention, what I claim is:

1. In a device for making spaced parallel ribs in sheets of metal for standing seam roofing, and the like, one of said ribs being located on each longitudinal edge of said sheets and the ribs of one edge of one sheet being adapted to be fitted over the rib on the opposite edge of an adjacent sheet and said device having a base, a frame carried on said base, and a plurality of shafts rotatably carried transversely of said frame, said shafts being arranged in vertically spaced parallel pairs: a cylindrical roller carried on each of said shafts, a die carried at op-

posite ends of each of said rollers, said dies being arranged to perform successive bending operations on a sheet of metal passing from the front to the rear of said frames and between said rollers, said dies having alined inner edges on each side of said frames whereby said metal is formed with a central portion of uniform width throughout its length, said dies along one end of said rollers being shaped to form a narrow rib upstanding from said sheet in inwardly spaced relation to the adjacent longitudinal edge of said sheet, said dies along the opposite end of said rollers being shaped to form a wider rib which will fit over said narrow rib, and means to control and assist in the final shaping of said narrow rib comprising a rigid guide carried by said frame, an arcuately shaped end portion on said rigid guide adapted to engage the end of a partially formed narrow rib and guide same into alinement with the final die, and a guide roller carried by said frame in slightly spaced relation to said rigid guide, said guide roller having its rotative axis extending normal to a sheet passing thereunder and having a cylindrical shape so as to engage the other side of said narrow rib opposite said rigid guide and assist in forming same in conjunction with said rigid guide whereby said narrow rib will be directed into said final guide in substantially finished condition.

2. The structure as set forth in claim 1 and a bend on the forward end of said gauge forming a guide to pick up and lead sheets of material into said rollers and dies.

3. In a device for making spaced parallel ribs in sheets of metal for standing seam roofing, and the like, one of said ribs being located on each longitudinal edge of said sheets and the ribs of one edge of one sheet being adapted to be fitted over the rib on the opposite edge of an adjacent sheet and said device having a base, a frame carried on said base, and a plurality of shafts rotatably carried transversely of said frame, said shafts being arranged in vertically spaced parallel pairs: a cylindrical roller carried on each of said shafts, a die carried at opposite ends of each of said rollers, said dies being arranged to perform successive bending operations on a sheet of metal passing from the front to the rear of said frames and between said rollers, said dies having alined inner edges on each side of said frames whereby said metal is formed with a central portion of uniform width throughout its length, said dies along one end of said rollers being shaped to form a narrow rib upstanding from said sheet in inwardly spaced relation to the adjacent longitudinal edge of said sheet, said dies along the opposite end of said rollers being shaped to form a wider rib which will fit over said narrow rib, and means to control and assist in forming said wider rib to insure its fitting over said narrow rib comprising a pair of rollers carried by said frame in spaced relation to each other in a position to receive said wider rib therebetween, said rollers having their rotative axes normal to a sheet passing through said machine and having cylindrical peripheries adapted to engage said rib on opposite sides thereof and to substantially complete the forming of said wider rib, an elongated guage member of substantially the same thickness as said narrow rib, means mounting said guage member longitudinally of said frame on one edge thereof intermediate said rollers and extending into the final die on said shafts whereby said rollers and final die cannot form said wider rib of less than a predetermined minimum thickness.
